WATCH

Willi A. Büchler, Thoune, Switzerland

Application March 21, 1946, Serial No. 655,909
In Switzerland March 19, 1945Section 1, Public Law 690, August 8, 1946
Patent expires March 19, 1965

4 Claims. (Cl. 58—74)

1

This invention relates to watches with a two-part winding stem.

An object of the invention is to provide a watch of this kind which is characterized in that the winding stem is axially displaced for executing three operations, on displacement for two of these operations the mutual position of the two parts of the winding stem remaining unchanged, while for the third operation the relative axial position of these parts is changed.

My invention may for instance be used in watches with centre seconds hand, the first two operations being then used for winding and hour setting and the third operation, for bringing back the seconds hand to its zero position or in chronographs for setting in motion and stopping the seconds hand. Of course any operation quite apart from the above mentioned one can be done in this third operating position.

Other objects and features will be apparent as the following description proceeds, illustrating two embodiments of the invention, reference being had to the accompanying drawings, wherein;

Fig. 1 represents an embodiment in which the third operating position serves to act upon the resetting or flyback member for resetting a centre seconds hand.

Fig. 2 is a further embodiment of the winding stem.

In Fig. 1 the crown is designated by 1 which with the tube-shaped part 2 forms the upper cylindrical extension 3 of the winding stem. The other part 4 ends in a small piston 5 with a guide-slot 6. A spring 7 is inserted between this piston 5 and the bottom of the cylinder 3. A pin 8 attached to the cylinder 3 slides axially with respect to the piston 5 and is borne in the guide-slot 6, so that the two parts of the winding stem are firmly coupled together so that transmission of rotary movement from one part to the other is ensured.

A resetting member, partially shown at 9, is connected to the winding stem by non-represented elements ending at the lever 11 which bears a pin 18, said pin being in the operating field of the rim 12 of the extension 3. The resetting member cooperates with the heart-shaped cam 10.

The drawing shows the winding stem in its extreme pulled out or hour adjusting position. The pin 8 lies at the upper end of the guide-slot 6 which limits the relative movement of the two parts 3 and 4. The winding stem can be brought into a second operating position by pressing the assembly constituted of the crown 1 and its cylin-

drical extension 3 partly downwards. On this movement, the elastic force of the spring 7 is greater than the resistance which is opposed by the mechanism for adjusting the hour. For this reason, the mutual position of the parts 3 and 4 remains unchanged and the whole stem is thus pushed downwards in that the uncompressed spring transmits the movement of part 3 and part 4. The third position is obtained by pressing the upper part of the winding stem completely inwards, so that the part 4 strikes against the part 19 forming a stop means and the spring 7 will be squeezed together, whereby the upper part 3 of the stem will be displaced inwards with respect to the lower part 4 which remains at rest. This displacement is limited by the length of the guide-slot 6 in which the pin 8 slides. The lever 11 to be driven during the last mentioned displacement is operated by the rim 12 of the cylindrical extension 3 which will come up against the pin 18 of the lever 11 and can, as already mentioned, control any operation within the watch. In the particular case considered, those components operate the resetting member 9 which re-conducts the seconds hand to its zero position by the intermediary of the heart-shaped cam 10. In the case of chronographs, this third displacement or supplementary operation may be used for alternately releasing and locking the seconds hand.

Fig. 2 shows a second embodiment of the winding stem, which differs from the first as to the way of conveying the displacement and the rotary movement to the lower half of the stem in the extreme pulled out position. Whereas in the first embodiment the rotary movement is transmitted by means of a device consisting of a pin 8 sliding axially within a guide-slot 6, in the second embodiment the same operation is done by means of a square shaped head piston 13 moving within a tubular extension 14. In the pulled out position of the first embodiment the lower half of the winding stem was pulled out into the position of adjusting the hour on account of the pin 8 coming up against the upper end of the slot 6 thus conveying its movement to the lower part 4. The corresponding element in the second embodiment in question is formed by the bent-in rim 15 which enters between the head piston 13 and a shoulder 16 beneath the square head piston 13. During the relative displacement between the two parts of the winding stem, the bent-in rim 15 slides over the thinner cylindrical part 17, and comes up against a pin like 18 fixed to a lever like 11, so that said rim operates a mechanism

which can also, for instance, comprise a resetting member 9.

In this way, it is possible without additional operating outer components in watches in particular with the seconds hand in the middle and also in chronographs to make one more operation possible than has been obtained with winding stem devices up to the present day.

What I claim is:

1. In a time piece, a case portion, a stop means, a winding stem mounted rotatably and axially adjustably on said case portion, said winding stem comprising an individual outer portion and an individual inner portion movable into engagement with said stop means and coupled with said outer portion for rotary motion and for mutual axial displacement of said portions, a resilient means inserted between said portions to space them axially of each other and to maintain the mutual axial position of said portions on an axial movement of said winding stem unchanged until said inner portion is stopped by said stop means, and a control means engageable with said outer portion on a relative axial movement of the latter with regard to said inner portion against the constraint of said resilient means.

2. In a time piece, a case portion, a stop means, a winding stem mounted rotatably and axially adjustably on said case portion, said winding stem comprising an individual outer portion and an individual inner portion movable into engagement with said stop means and coupled with said outer portion for rotary motion and for mutual axial displacement of said portions, a spring inserted between said portions to space them axially of each other and to maintain the mutual axial position of said portions unchanged on an axial movement of said winding stem from an hour adjusting position to a winding position until said inner portion is stopped by said stop means, and a seconds hand-control means engageable with said outer portion on a relative axial movement of the latter with regard to said inner portion against the constraint of said spring.

3. In a time piece, a case portion, a stop means, a winding stem mounted rotatably and axially adjustably on said case portion, said winding stem comprising an individual outer portion and an individual inner portion movable into engagement with said stop means and coupled with said

outer portion for rotary motion and for mutual axial displacement of said portions, a spring inserted between said portions to space them axially of each other and to maintain the mutual axial position of said portions unchanged on an axial movement of said winding stem from an hour adjusting position to a winding position until said inner portion is stopped by said stop means, and a center-seconds hand-resetting member engageable with said outer portion on a relative axial movement of the latter with regard to said inner portion against the constraint of said spring.

4. In a time piece, a case portion, a stop means, a winding stem mounted rotatably and axially adjustably on said case portion, said winding stem comprising a cylindrical hollow portion and a piston-like portion fitting slidably in said cylindrical hollow portion, a slot on one of said portions and a pin on the other portion, engaging said slot to couple said portions for rotary motion and for a limited mutual axial displacement, a spring inserted in said cylinder and supported on the latter and on said piston-like portion to space said portions axially of each other and to maintain the mutual axial position of said portions unchanged on an axial movement of said winding stem from an hour adjusting position to a winding position until said piston-like portion is stopped by said stop means, and a control means engageable with said cylindrical hollow portion on a relative axial movement of the latter with regard to said piston-like portion against the constraint of said spring.
